UNITED STATES PATENT OFFICE.

ANSON HENRY CRESSY, OF HARTINGTON, NEBRASKA.

SPARK-PLUG.

1,313,522.

Specification of Letters Patent. Patented Aug. 19, 1919.

Application filed December 5, 1916. Serial No. 135,218.

To all whom it may concern:

Be it known that I, ANSON H. CRESSY, a citizen of the United States, residing at Hartington, in the county of Cedar and State 5 of Nebraska, have invented new and useful Improvements in Spark-Plugs, of which the following is a specification.

This invention relates to spark plugs the broad object in view being to provide in connection with a spark plug, means whereby burned explosive mixture and lubricating oil may be positively excluded from the points of the electrodes during the firing and exhaust strokes of the piston, thus keeping 15 the spark points or electrodes clean and in perfect working condition at all times.

A further object in view is to provide in connection with a spark plug formed with a combustion cavity, a valve attached to the 20 plug and operating automatically during the different cycles of the piston to close said combustion cavity against the admission of burned mixture and lubricating oil, said valve being opened by excessive pressure upon the same caused by the ignition and expansion of explosive mixture within 25 the combustion cavity of the plug.

With the above and other objects in view, the invention consists in the novel construction, combination and arrangement of parts, 30 herein described, illustrated and claimed.

In the accompanying drawing:

Figure 1 is a diametrical section through a spark plug embodying the present invention. 35

Fig. 2 is a detail perspective view of the valve detached.

Fig. 3 is a fragmentary section on the same line as Fig. 1 showing another form 40 of valve.

Fig. 4 is a bottom plan view of a spark plug embodying the valve shown in Fig. 3.

Referring to the drawings A designates generally a spark plug of the conventional 45 type embodying the outer shell 1, the insulating core 2, the core clamping nut 3, the central longitudinally extending power electrode 4, and the electrical conductor or wire clamping nut 5, said parts being of the ordinary construction and relative arrangement.

In carrying out the present invention, I employ an externally threaded valve seat member 6 having at its outer end a circumferential flange 7 formed at diametrically 55 opposite points with notches 8 to receive the

extremities of a wrench or spanner to enable said valve seat to be screwed into place or removed therefrom, the inner end of the body or shell of the plug being internally threaded as shown to enable said valve seat to be screwed into and removed from the same. The valve seat is of tubular or hollow formation and provides in connection with the interior of the shell 1 a combustion cavity 9. The bore of the valve seat member is smooth and is adapted to admit of the reciprocatory movement of the tubular stem 10 of a valve body 11, the tubular stem 10 being formed with ports 12 to allow fresh mixture to enter the combustion cavity of the plug and the ignited mixture to expand and escape therefrom while in, a burning condition.

The valve body is shown as provided with a conical or beveled working face 13 while the valve seat member is formed with a corresponding working face 14. The inner edge of the tubular stem of the valve is spun or swaged outwardly to form a retaining annular lip or flange 15 which contacts with the inner extremity of the valve seat member and limits the outward or opening movement of the valve. The valve body is also formed with a diametrical niche 16 so that by means of a screw-driver, the valve may be oscillated for the purpose of grinding the working face of the valve body and valve seat. The ground electrode 17 is attached to and carried by the inner face of the valve body and is shown as directly lying opposite the extremity of the power electrode.

The operation of the plug in actual use may be described as follows: The valve works automatically and is controlled by and in accordance with the cycles of the piston. Commencing with the intake stroke of the piston, the valve opens and the combustion cavity in the plug fills with gas drawn into the combustion chamber of the cylinder by the suction stroke of the piston. During the compression stroke of the piston, the valve automatically closes and remains closed until the compression stroke is completed, so that at the conclusion of the compression stroke there is a charge of explosive mixture in the combustion cavity of the plug which is under less compression than the main charge in the cylinder. Then the explosive mixture, trapped in the combustion cavity of the plug by the automatic closing of the plug is ignited and in ex-

panding, forces said valve open, escaping from the combustion cavity of the plug in the form of flame and igniting the mixture contained in the combustion chamber of the 5 cylinder. By the expansion of the mixture in the combustion chamber of the cylinder during the firing or working stroke of said piston, the valve of the plug is again closed and remains so until the completion of the 10 exhaust stroke of the piston. Thus the valve serves to exclude from the combustion cavity of the plug and from the electrodes thereof, oil, carbon, burned gases and other foreign matter, keeping the electrodes in perfect 15 working condition.

In addition to the foregoing, certain special effects are obtained by the use of the described structure in a spark plug, such effects being based or dependent upon the 20 physical law, which may be stated as follows: The dielectric strength of gases varies directly as the absolute pressure and inversely as the absolute temperature. Thus as the charge in the combustion cavity of 25 the plug is under comparatively low compression, the spark will pass much more readily between the electrodes than it would if the electrodes were located in the main chamber or engine cylinder where it would 30 be necessary to break down the high dielectric strength of the highly compressed main charge. Furthermore, since the valve itself forms one of the electrodes, and as the valve will commence to open immediately upon 35 ignition of the auxiliary charge in the combustion cavity of the plug, it will thereby increase the length of the gap or sparking distance between the electrodes, and the spark will be drawn out or elongated as the 40 dielectric strength of the gas between the electrodes is further lowered by the increase of temperature thereof. The described effects result in the production of a spark sufficient to ignite the charge under conditions 45 such that no spark would occur with a plug having a fixed distance or gap between the electrodes, and with which the gap is filled with portions of a highly compressed charge. 50 It will, of course, be understood that other forms of valves may be employed as well as the form illustrated in Figs. 1 and 2. For example, a spherical or ball valve 18 may be employed as shown in Figs 3 and 4 and the 55 valve seat member 19 which screws into the casing 1 may be provided with valve retaining fingers 20 to hold the valve in place and admit of the necessary movement of said valve toward and away from its seat 21. The 60 size and formation of the valve may thus be varied in accordance with the will of the manufacturer without departing from the

principle or sacrificing any of the advantages of the invention.

I claim:

1. A spark plug having a combustion cavity in the inner portion thereof and having a valve seat formed at the inner portion of said cavity, in combination with a valve movable toward and from said valve seat to close and open said end of the combustion cavity to entrap therein and release therefrom portions of an explosive gaseous charge, said valve forming one electrode of the plug and a second electrode disposed 75 within said combustion cavity, whereby a spark passing between said valve and said second electrode may ignite the charge entrapped in said cavity and open the valve and explode the charge within the combustion 80 chamber of the engine.

2. Charge-igniting means for internal combustion engines, comprising a spark plug having a combustion cavity in the inner portion thereof, a valve seat formed at the 85 inner end of said cavity, and a fixed electrode terminating in said cavity, in combination with a valve coöperable with said seat, to close said combustion cavity, said valve being proportioned and arranged so as to be 90 closed by gas pressure during the compression stroke of the piston to thereby entrap in said combustion cavity a portion of the explosive charge prior to full compression thereof, and said entrapped charge being 95 ignited by a spark passing from said fixed electrode through a part of the combustion cavity of the plug.

3. Charge-igniting means for internal combustion engines, comprising a spark plug 100 having a combustion cavity formed therein, an electrode terminating in said cavity, and means adapted to automatically close combustion cavity during the compression stroke of the engine piston and to thereby entrap 105 in said cavity a portion of the explosive charge prior to full compression thereof, said means movable toward and from said electrode and forming a second electrode located within the cavity when the same is 110 closed.

4. A spark plug provided with a combustion cavity and having a valve automatically operable by the pressures in the combustion chamber or engine and adapted to confine 115 a charge of explosive mixture within the said cavity on the compression stroke of the engine and means carried by the spark plug for igniting the charge within its cavity to cause the ignited charge to open the valve 120 and ignite the charge within the combustion chamber of the engine.

In testimony whereof I affix my signature.
ANSON HENRY CRESSY.
